CHILD CARRIER FOR BICYCLE

Irvin E. Berger, Skokie, and John Peter Ronvik, Palos Heights, Ill., assignors to Sears, Roebuck and Co., Chicago, Ill.

Filed Apr. 14, 1972, Ser. No. 244,318

Term of patent 14 years

Int. Cl. D6—01; D12—16
U.S. Cl. D90—16

Fig. 1

Fig. 2

Fig. 3

Fig. 4

FIG. 1 is a front perspective view of a child carrier for bicycle showing my new design.

FIG. 2 is a top perspective view thereof.

FIG. 3 is a rear perspective view thereof; and

FIG. 4 is a side elevational view thereof showing its use with a bicycle, with the bicycle and supporting bracket being shown in broken lines for illustrative purposes only.

The side of the child carrier for bicycle not shown is substantially similar in appearance to the side shown.

We claim:

The ornamental design for a child carrier for bicycle, as shown and described.
